UNITED STATES PATENT OFFICE.

CHARLES A. COWLES, OF ANSONIA, CONNECTICUT.

MACHINE FOR STRINGING DRAWING-DIES UPON WIRE.

SPECIFICATION forming part of Letters Patent No. 619,723, dated February 21, 1899.

Application filed February 23, 1897. Serial No. 624,692. (No model.)

To all whom it may concern:

Be it known that I, CHARLES A. COWLES, of Ansonia, county of New Haven, State of Connecticut, have invented a new and useful Improvement in Machines for Stringing Drawing-Dies upon Wire, of which the following is a specification, reference being had to the accompanying drawings.

I will describe a machine embodying my improvement and then point out the novel features in claims.

In the accompanying drawings, Figure 1 is a front elevation of a machine embodying my improvement, certain parts being broken away and others being shown in section. Fig. 2 is a top view of the machine. Fig. 3 is a transverse vertical section taken as indicated by the dotted line xx , Fig. 1. Fig. 4 is a horizontal section taken as indicated by the line yy , Fig. 1. Fig. 5 is a front elevation of a portion of the machine, illustrating a modification. Fig. 6 is a transverse section of the same. Fig. 7 is a front elevation of a machine of modified form embodying the improvement, certain parts being broken away and others being shown in section. Fig. 8 is a front elevation of certain parts of the machine shown in Fig. 7, showing parts in different positions. Fig. 9 is a transverse vertical section at the plane of the dotted line vv , Fig. 7. Fig. 10 is a top view of the machine. Fig. 11 is a transverse vertical section taken as indicated by the dotted line ww , Fig. 7. Fig. 12 is a longitudinal vertical section of gripping-jaws comprised in the machine. Fig. 13 is a horizontal section of the same. Fig. 14 shows the wire with drawing-dies strung upon it as such wire will be taken from the machine.

Similar letters of reference designate corresponding parts in all the figures.

Referring to Figs. 1, 2, 3, and 4, A designates the framework, consisting of a front piece a' , a rear piece a'' , and cross-pieces or stretchers a^3 . In the front and rear pieces of the framework a shaft B is journaled. On the front end of this shaft is loosely mounted a head C, which carries a pair of jaws C', these jaws being connected so as to be capable of a swinging movement and also a sliding movement in the direction of their length. As here shown, the head C has a center hub c', that fits upon the shaft B, and at its circumference a

cylindric flange c², that extends rearwardly. Inside the flange is one part c³ of a clutch C², the other part c⁴ of this clutch being fitted to slide lengthwise of the shaft B and engage to rotate therewith by means of a spline. The clutch here shown is a ratchet-tooth clutch, the sliding part of which is controlled at the pleasure of the operator, and when the sliding part is properly shifted the head will be instantaneously released and be permitted to rotate freely in a reverse or opposite direction. The sliding part c⁴ of the clutch is adjusted lengthwise of the shaft by means of a lever c⁵, which is here shown as fulcrumed by a pin c⁶ to a bracket c⁷. At its upper end it is bifurcated and provided with pins to engage with a circumferential groove in the part c⁴ of the clutch, and at its lower end it is pivotally connected by means of a pin c⁸ with one end of a rod c⁹, which at its other end is connected by a pin c¹⁰ with a lever c¹¹, that serves to operate another clutch presently to be described. The levers c⁵ c¹¹, thus connected by the rod c⁹, may be operated in any suitable manner—as, for instance, by a foot-lever c¹², which is fulcrumed by a pin c¹³ to a stand c¹⁴ and connected by a link c¹⁵ to the lever c⁵. It will be seen that the foot-lever c¹² is of such shape that the attendant can by pressure of his foot upon different portions move the levers c⁵ c¹¹ in either direction. I do not wish to confine myself to operating both the levers c⁵ c¹¹ together, as illustrated, as a foot-lever c¹² might be used for each independently of the other.

Upon the shaft B is affixed a gear-wheel b, and this engages with a gear-wheel b', affixed to a shaft b², which is intended to be journaled in the front and rear pieces of the framework A, although in Fig. 3 it is shown as broken away, so as not to extend to the front piece of the framework. Upon the shaft b² is also affixed a gear-wheel b³, which engages with a gear-wheel b⁴. This gear-wheel b⁴ is affixed to the hub of one part b⁵ of a clutch, whose other part b⁶ is affixed upon a shaft b⁷, that is journaled in the front and rear pieces a' and a'' of the framework A. This is constantly driven, it being in the present instance provided with a pulley p, by which it may derive motion through a belt. The part b⁵ of the clutch is free to turn inde-

pendently of the shaft b^7 , upon which it is mounted.

The clutch, as here shown, is of a kind which is well known in the art, and its part b^5 has a 5 split ring whose ends may be drawn together by the oscillation of an arm b^8 to embrace the part b^6 of the clutch. For oscillating the arm b^8 in such a manner as to tighten the split ring I mount upon the shaft b^7 a cone b^9 in 10 such a manner that it may be moved lengthwise of the shaft b^7 . A convenient means for moving the cone is a lever b^{10} , fulcrumed by a pin b^{11} to a bracket b^{12} , extending rearwardly from the front piece a' of the framework A. 15 This lever is bifurcated to embrace the cone and is pivotally connected thereto by pins b^{13} . The lever is extended downwardly beneath the cone, so that it may be acted on by a wedge b^{14} , which is supported upon a bracket b^{15} , 20 extending rearwardly from the front piece a' of the framework A. The purpose of this wedge is to automatically stop the head C from rotating, as will be hereinafter more fully set forth. On the shaft b^7 is affixed a gear-wheel 25 b^{16} , which engages with a gear-wheel b^{17} , that is affixed to a shaft b^{18} , which is journaled in the front and back pieces a' and a^2 of the framework A. This shaft b^{18} operates the dies employed for pointing or swaging the end of 30 the wire preparatory to drawing the wire through the drawing-dies. Any form of swaging device may be used in connection with my machine—such, for example, as the "Dayton" swaging-machine—and hence I do not 35 deem it necessary to describe any particular swaging or pointing mechanism.

Upon the hub of the part b^5 of the clutch at one side of the gear-wheel b^4 a sprocket-wheel b^{19} is affixed. From it extends a sprocket-chain b^{20} to a sprocket-wheel b^{21} , mounted loosely upon a shaft b^{22} , that is journaled in any suitable framework—as, for instance, in brackets extending from the front and back pieces a' and a^2 of the framework A. At one 45 end of the hub of the sprocket-wheel is one part b^{23} of a two-part ratchet-clutch. The other part b^{24} of said clutch is fitted upon the shaft b^{22} , so that it may slide lengthwise thereof, but is connected by a spline, so that it 50 must rotate with the shaft.

The lever c^{11} , which I have heretofore explained as being capable of adjustment by means of the foot-lever c^{12} , has its upper end bifurcated to engage with a circumferential 55 groove with which the part b^{24} of the clutch is connected. This lever is fulcrumed by a pin c^{20} to a bracket c^{21} , that extends from an arm attached to the back piece a^2 of the framework A. When the part b^{24} of the clutch is 60 moved into engagement with that part of the clutch which is affixed to the sprocket-wheel b^{21} , rotary motion will be imparted by the sprocket-wheel to the shaft b^{22} . Upon this shaft b^{22} is affixed a windlass b^{25} , around and 65 from which a rope b^{26} may be wound and unwound. At one end of the windlass a ratchet-wheel b^{27} is provided, so as to turn with the

windlass, and with which coacts a pawl b^{28} , pivotally connected by a screw b^{29} to a bracket extending from the front piece a' of the framework A. Normally this pawl b^{28} is in engagement with the ratchet-wheel b^{27} , so that unless it is thrown out of engagement by the hand of the attendant the rope b^{26} will be incapable of unwinding. 75

Affixed to the shaft b^{22} is a pinion b^{30} , which engages with a gear-wheel b^{40} , that is loosely mounted upon a stud b^{41} , carried in the bracket extension on the part a^3 , and affixed to the gear-wheel b^{40} is a pinion b^{42} , which is in 80 engagement with a gear-wheel b^{43} , loosely mounted on the shaft b^{22} . The gear-wheel b^{43} is provided on its face with a dial b^{44} , and adjacent to the dial is affixed an index-finger b^{45} , also carried on the bracket extension. 85

s represents a hand-crank provided on the shaft b^{22} for turning the windlass.

The rope b^{26} extends around the guide-pulley b^{30} , which is supported by a post b^{31} , extending upwardly from the floor. From this 90 guide-pulley the rope descends downwardly to support a weighted pulley b^{32} . After passing through this weighted pulley the rope extends upwardly to an arm b^{33} , which I have shown as extending from the post b^{31} . Upon the rope 95 b^{26} a projection b^{34} is arranged. With this arrangement of parts the rope b^{26} , carrying the projection b^{34} , will when wound upon the windlass engage with the arm d , carried by the slide-piece D, so that when a sufficient number of feet of wire have been drawn through 100 the first die the slide-piece can be made to move forward and stop the rotating of the head. The mechanism operated by the slide-piece for stopping the rotation of the head 105 consists of an arm d^4 , that projects from its rear to engage the wedge b^{14} and move it in such direction that it will by acting upon the lever b^{10} move the cone b^9 away from the arm b^8 . Thus the split ring of the clutch b^5 b^6 110 will be loosened, so that motion will no longer be transmitted from the shaft b^7 except to that shaft b^{18} which operates the wire-pointing dies.

The shank of the wedge b^{14} works in guides 115 b^{35} . A shoulder b^{36} , formed at the junction of the wedge with its shank, acts against the guide b^{35} to limit the return movement of the wedge, and consequently of the slide-piece.

Between the guide b^{35} and the collar b^{37} , 120 which is affixed to the shank of the wedge, a spring b^{38} is coiled. This spring serves to move the wedge in such a direction as to allow the lever b^{10} to be manipulated to throw the cone b^9 forward in order that it may disengage the two parts of the clutch b^5 b^6 . It 125 also serves to move the slide-piece D back to the starting position.

The operation of this form of device is as follows: The rope b^{26} is wound upon the windlass by the hand-crank s until the projection b^{34} is in such a position that when the windlass is operated by the hereinbefore-described mechanism the projection will engage with 130

the arm d to move the sliding piece D forward. The end of the wire is pointed in the swaging mechanism carried by the machine and its end inserted through the die, which is placed in the die-holder E , and the swaged or pointed end gripped by the jaws carried by the head. The machine is then started by pulling down the lever b^{10} to throw the cone into engagement with the split collar, so that the disk b^5 will be rotated. At the same time the foot-lever c^{12} is operated to throw the clutch c^4 into engagement with the clutch-face carried by the head and the clutch b^{24} into engagement with the clutch-face b^{23} . As the head is rotated it draws the wire through the die, and at the same time the rope is wound upon the windlass to cause the projection b^{34} to engage with the arm d . As soon as the projection b^{34} comes into engagement with the arm d the slide D is moved forward, which in turn causes the wedge-shaped block b^{14} to engage with the lower end of the lever b^{10} to move the cone b^9 out of engagement with the split ring and in this manner stop the machine. The wire coiled upon the head is loosened by the reverse movement of the head and removed therefrom with a die remaining on the wire, and the coil, with the die, is supported on either the hook d^2 or d^3 . The wire is again pointed by the swaging device carried by the machine, a smaller die placed on the wire, and the operation repeated. It will be understood that after the machine is stopped the pawl b^{28} is moved out of engagement with the ratchet b^{27} to allow the weighted pulley b^{32} to return the projection and thus permit the wedge b^{18} to be returned to its normal position by the spring b^{38} . The jaws C' are formed upon levers c^{16} c^{17} , which are pivoted together between their ends by a pin c^{18} . The jaws are at one end of the levers. At the other end the levers are made to embrace a wrist-pin c^{20} , extending from the rotary head C . The surfaces of the levers which embrace this wrist-pin converge toward the extremities of the levers, so that any strain lengthwise on the levers will cause the wrist-pin to have a cam-like action on the ends of the levers with which it coacts. This of course will cause the jaws at the other end of the levers to grasp the end of wire which is between them more tightly. Adjacent to the jaws is a holder E for a drawing-die e . The end of a piece of wire to be drawn having been pointed is passed through a drawing-die, and while the latter is supported by the die-holder E the end of the wire is placed between the jaws C' . The machine being started the wire will be drawn through the drawing-die for any desired length. Adjacent to the jaws C' the rim c^2 of the rotary head C is provided with an incline or notch c^{21} , that drags the wire onto the outer surface of said rim c^2 . The wire will be wound by the rotation of the head around this rim c^2 until a sufficient amount has been drawn through the die which is at the time supported by the

die-holder E . When the machine is automatically stopped in the manner described, the rotary head C suddenly reverses, caused by a strain upon the wire. Perhaps sometimes the ratchet-clutch c^3 c^4 conduces to this. One diametrical half of the head C is made heavier than the other, so that when it stops its movement in the reverse direction the jaws C' will be above the shaft B . This is due to recessing one portion of the head. The recess thus formed is advantageous for accommodating the jaws as the head rotates. This reverse motion of the head causes the jaws to loosen their hold upon the wire, and as the coils by their resilience will enlarge they are readily removed from the head. A coil having the die upon it will be held upon the hook d^2 , and the other coils may be held in the hand of the operator in the position of the coil w in Fig. 1. The operation is then repeated with a die of smaller size, and so on until the wire is threaded through the proper number of dies, from where it is taken to a wire-drawing machine and strung thereon in the usual manner.

Referring now to Figs. 5 and 6, I need only add to the description already given of my machine that the slide-piece D has attached to it the scale d^5 , the attachment being made, as here shown, by the arm d^6 . The face of the scale d^5 is grooved and has a slide-piece d^7 , carrying the arm d , fitted to it in such a way that it may be clamped in different positions by means of a thumb-nut d^8 . The arm d may be conveniently adjusted on the scale by means of the slide and thumb-nut. The operation of this form of device is similar to that described in connection with the form of machine shown in Figs. 1 to 4. The arm d is adjusted on the scale to the position where the projection b^{34} is to engage it to move forward the slide-piece D and put in operation the mechanism hereinbefore described to stop the machine.

I will now turn to Figs. 7, 8, 9, 10, and 11. Here the shaft B has combined with it the rotary head C in the same manner as already described in connection with Figs. 1, 2, 3, and 4, and it also has affixed to it a gear-wheel b . This gear-wheel engages with the gear-wheel b^{46} , which surrounds the shaft b^{47} , having affixed to it a gear-wheel b^{48} , that engages with a gear-wheel b^{49} , affixed to a shaft b^{50} . This shaft b^{50} has affixed to it a belt-pulley by which motion may be transmitted to this shaft. With the shaft b^{47} the clutch b^5 , b^6 , and b^8 is combined in the same way that the said clutch was combined with the shaft b^7 in the example of my improvement illustrated by Figs. 1, 2, 3, and 4. This clutch is controlled by a lever b^{10} and a wedge b^{14} , and these parts operate as already described in connection with the example of my improvement illustrated in Figs. 1, 2, 3, and 4. The gear-wheel b^{46} , which I have described as surrounding the shaft b^{47} , is affixed to the hub of the part b^5 of the clutch. It will be understood that when the lever b^{10}

is suitably shifted by hand or by the wedge b^{14} it will disengage the part b^5 of the clutch, and hence the gear-wheel b^{46} , from the shaft b^{47} and will thereby stop the rotation of the 5 shaft B and head C. The wedge b^{14} has its shank supported by the guide b^{51} and has affixed to it two collars b^{52} and b^{53} . These collars coact with the arm d, which is affixed to the slide-piece D. The collar b^{52} limits the 10 movement of the wedge in one direction by coming in contact with the guide b^{51} . The collar b^{53} and the arm d contact, and the latter moves the wedge forward in the proper direction to stop the rotation of the head C 15 by acting upon the lever b^{10} . A spring b^{54} surrounds the shank of the wedge between the guide-bracket b^{55} and the collar b^{56} . This spring moves the wedge into inoperative position and also, through the contact of the 20 collar b^{53} with the arm d, starts the movement of the slide-piece D in the direction away from the rotary head C. The die-holder E supports the drawing-die e to be threaded. As here shown, the die-holder is pivotally connected with the front piece of the framework A by means of a bolt e^{10} . The end of the wire is pointed and passed through the die and is 25 grasped by the jaws C'. The rotation of the head C winds up the wire upon it, drawing 30 it through the die e. After the coils of wire have been released from the rotary head they will be hung upon the hook d^{10} , as already described in connection with the first example of my improvement, and the operation re- 35 peated.

If preferred, the scale mechanism described in connection with the stringing mechanism may be dispensed with and the following arrangement of parts employed, which are 40 shown in Fig. 7: The slide-piece D is provided with a drum d^{10} and with a bifurcated protuberance d^{11} , which may also support the die. In this form the end of the wire is pointed, as usual, passed through the die, 45 and gripped by the jaws of the clamp C'. The machine is then started to draw a sufficient amount of wire through the die, which may be determined by the diameter of the head C or the number of coils of wire drawn 50 around the head, after which the machine is stopped and the drawn wire removed. The end of the wire is again pointed and gripped by the jaws of the clamp, the first die being held by the bifurcated protuberance d^{11} , carried 55 on the slide-piece D, which for this operation is moved away from the head a certain distance and a portion of the drawn wire between the die and the head is wrapped around the drum d^{10} . The machine is started 60 and the wire drawn through the die until the wire tightens around the drum d^{10} , at which time the slide-piece D will be drawn toward the head until it reaches the end of its movement, at which time the machine is stopped 65 and the wire drawn through removed from the drum. This operation is again repeated until all the dies are strung upon the wire, it

being understood that the slide-piece D is moved back before the beginning of each drawing subsequent to the first, the die placed 70 in the holder d^{11} , and a portion of the wire wrapped around the drum d^{10} . With this arrangement I have found in practice that the dies will be strung accurately upon the wire, so that the wire can be readily placed in position on a drawing-machine. 75

What I claim as my invention is—

1. In a machine for stringing dies upon wire, the combination of a drawing-head capable of rotation in two directions, means for rotating 80 said head in one direction to draw the wire through a die, a device for controlling said means to stop the further rotation of the head and permit the head to rotate freely in a reverse or opposite direction to relax the tension upon the wire, and automatic means for gripping and releasing the end of the wire, substantially as described.

2. In a machine for stringing dies upon wire, the combination of a drawing-head capable of 90 rotation in two directions, jaws carried by said head for gripping the end of the wire as the head is rotated in one direction, means for rotating said head in one direction to draw the wire through a die, a ratchet-clutch in said 95 means adapted when thrown into action to instantly start said head in the drawing direction and when thrown out of action to instantly stop the rotation of the head to permit it to rotate freely in a reverse or opposite direction, 100 and a lever mounted independently of said head for throwing said clutch into and out of action, substantially as described.

3. In a machine for stringing dies upon wire, the combination of a drawing-head capable of 105 rotation in two directions, means for rotating said head in one direction to draw the wire through a die, and a device for controlling said means to stop the further rotation of the head and permit the head to rotate freely in 110 a reverse or opposite direction to relax the tension upon the wire; gripping-jaws, hinged together and having cam-surfaces, and a projection carried by the head and co-operating with said cam-surfaces, so that when the head 115 rotates in the drawing direction the jaws are actuated to grip the wire and when the head rotates in the reverse direction they are permitted to release the wire, substantially as specified. 120

4. In a machine for stringing dies upon wire, the combination with a rotating head provided with jaws, of a die-holder, means for rotating the head, a ratchet-clutch in said means for instantly stopping the rotation of said head, 125 and a friction-clutch also in said means for gradually starting the rotation of said head, substantially as specified.

5. In a machine for stringing drawing-dies upon wire, the combination of a rotating head 130 carrying gripping-jaws, means for rotating said head comprising a clutch, and a sliding piece for carrying the wire adapted to operate said clutch when drawn toward the head to

prevent the further rotation of the head, substantially as described.

6. In a machine for stringing drawing-dies on wire, the combination of a drawing-head provided with gripping-jaws, means for rotating said drawing-head comprising a clutch, the die to be strung on the wire, and a piece adapted to slide toward the head at intervals and to operate the clutch to prevent further rotation of said head, substantially as described.

7. The combination of a rotary head made heavier on one diametrical half than the other, a pair of jaws connected with the lighter diametrical half of said head, and means comprising a clutch for rotating said head, substantially as specified.

8. The combination with a rotary head provided with jaws, means for rotating the said head in one direction and permitting it to move in another direction, of a piece carrying supports for wire threaded with drawing-dies adapted to engage the means for rotating the head to stop the rotation of the head, and means independent of the wire for moving said piece toward the rotating head, substantially as described.

9. The combination with a rotary head provided with jaws, and means for rotating the said head in one direction and permitting it to move in another direction, of a piece carrying supports for the wire threaded with drawing-dies, means for moving said piece toward the head, and a clutch located in the said means for rotating the head adapted to be operated to prevent the further rotation of the head, substantially as specified.

10. The combination with a rotary head provided with jaws, and means for rotating the said head in one direction and permitting it to move in another direction, of a piece carrying supports for wire threaded with drawing-dies, said piece being movable toward and from the rotary head, and a stop mechanism for the rotary head operated by said movable piece, substantially as specified.

11. The combination with a head provided with gripping-jaws and capable of rotation in two directions, one to move a wire along and the other to relax the tension upon the wire, a sliding piece carrying a wire strung with

drawing-dies and adapted in its movement toward the head to prevent the movement of the head for drawing, and a scale for determining the forward movement of the piece, substantially as described.

12. In a machine for stringing drawing-dies upon wire, the combination of a rotary head provided with gripping-jaws, means for operating said head, and a slide-piece for supporting the wire threaded with dies, said piece being movable toward and away from the head and adapted when moved forward to stop the rotating of said head, substantially as described.

13. In a machine for stringing drawing-dies upon wire, the combination of a drawing-head capable of rotation in two directions, operating mechanism for said head comprising a clutch, a die-holder, and a device adapted to be moved toward the drawing-head when the wire is being drawn for operating the clutch to stop the rotation of the head and allow it to rotate in a reverse direction, substantially as shown and described.

14. In a machine for stringing drawing-dies on wire, the combination of a drawing-head capable of rotation in two directions, operating mechanism for said head comprising a clutch, a die-holder, a device adapted to be moved toward the drawing-head when the wire is being drawn through the die, and means in connection with said device for causing it to act on the clutch at a predetermined period to stop the rotation of the head in the drawing direction, substantially as described.

15. In a machine for threading wire through dies, the combination of a die-holder, means for drawing the wire through a die in said holder, means for pointing or swaging the wire preparatory to threading the wire through the die, said pointing or swaging means being driven by the wire-drawing means, substantially as specified.

In testimony whereof I have signed my name to this specification in the presence of two subscribing witnesses.

CHARLES A. COWLES.
